LIQUID FUSE

Ralph H. Earle, Wauwatosa, Wis., assignor to
 Line Material Company, South Milwaukee,
 Wis., a corporation of Delaware

Application May 5, 1932, Serial No. 609,452

5 Claims. (Cl. 200—117)

This invention relates to liquid fuses.

Objects of this invention are to provide a novel form of liquid fuse which will respond to overloads whether suddenly or gradually applied, which will quickly separate the two portions of the fuse link when fusing occurs, and which will quickly withdraw one of the portions of the fuse link below the surface of an arc extinguishing liquid.

Further objects are to provide a fuse of this general type which is so constructed that the fuse link, although capable of being formed to respond to a small value of current, nevertheless is not subjected to undue or excessive mechanical strain, but which is so made that the fuse link and the method of anchoring the ends thereof provide mechanical strength to withstand the initial handling, while the device is being re-fused, and also to withstand the steady pull of a spring without danger of any of the parts failing from mechanical weakness.

Further objects are to provide a fuse in which the fuse link is of composite construction with the upper and lower parts soldered together but which is of great tensile strength, even at the soldered joint due to an overlapping face to face contact of flat, ribbon like members, preferably with the ribbon member of one part received between or intermeshing with two ribbon members of the other part.

When fuses having soldered portions are under mechanical strain, it has been found that with the usual type of soldered joint that such joint is frequently twisted, bent or otherwise placed in such a position it is subjected to tensile strain as well as pure shear. Under these conditions tests have shown that the action of the fuse is not wholly satisfactory. There seems to be somewhat of a gradual mechanical failing of the joint hastened whenever the joint is hot.

Further objects of this invention are to provide a novel form of fuse in which the soldered joint is in pure shear and cannot turn or be so positioned that it is subjected to tensile stresses, which would interfere with the accurate functioning of the fuse. Instead, the joint is so made that although a considerable mechanical stress or pull may be imparted to the joint, that nevertheless the soldered joint is itself in pure shear and consequently a gradual failing or an alteration of the accuracy of the fuse is avoided.

Further objects are to provide novel forms of attaching means for both the upper and lower ends of the fuse link to not only give an adequate and firm mechanical attachment for the ends of

the fuse link, but also to secure an unusually good electrical contact between the ends of the fuse and the adjacent conducting portions to which the fuse link is attached.

It has been found that with the usual types of fuses that accurate calibration is extremely difficult and that calibration is usually very uncertain, only a very rough approximation being secured.

This invention is designed to overcome the defects noted immediately above, and further objects of this invention are to provide a novel form of fuse in which accurate calibration may be obtained with the utmost facility, and in which the fuses, although made by quantity production, are nevertheless substantially uniform, and in which fuse strips of different values, that is to say different fusing current values, may be most easily constructed in a simple and relatively precise manner.

In greater detail, further objects of this invention are to provide a novel form of fuse which is so made that the I^2R watts developed is substantially constant at the soldered joint, irrespective of the current value for which the fuse is designed, the variation in current value for different sizes or capacity fuses being obtained by varying the composition of the fuse strips or members, or by varying their cross-sectional area, preferably by varying their thickness. This invention, therefore, provides a means whereby solder or other readily fusible material having a substantially definite fusing point may be used for all sizes or capacity of fuses, and in which the same dies may be employed, if desired, for stamping out the fuse strips or members of the same width, the variation in capacity of the fuse being obtained by varying the thickness.

Thus, this invention materially reduces the cost of manufacture of fuses and at the same time reduces the equipment necessary for making fuses of different capacities. Either one or both of the two ways of securing different value or different capacity fuses may be employed, or, if desired, solders of different fusing points may be employed, although it has been found that this last method is a great deal more unsatisfactory and less precise than to use solder of a definite melting point for all sizes of fuses and obtain the variation in rating or capacity of the fuse

by either of the two methods detailed hereinabove.

Embodiments of the invention are shown in the accompanying drawings, in which:—

Figure 15 is a sectional view on the line 15—15 of Figure 7.

Figure 16 is a sectional view on the line 16—16 of Figure 8.

35 Figure 17 is a sectional view on the line 17—17 of Figure 12.

Referring to the drawings, it will be seen that the liquid fuse comprises a tubular or cylindrical container 1, preferably of glass or other suitable 40 insulating material, which is provided with a lower metal cap or contact member 2 and an upper metal sleeve or contact member 3 each secured to the glass tubular body portion 1 in a gas and liquid tight manner.

45 The upper contact member, or sleeve 3, is externally threaded and receives the ring nut 4 which tightly clamps a gasket disk, or closure member 5, in place. The disk 5 is formed of a yielding and somewhat expansible material such 50 as lead, aluminum, tinfoil, or some other alloy which is soft and expansible.

This gasket disk 5, when clamped in place by the ring nut 4, forms a gas seal, and is adapted to be ruptured, and the part closing the opening 55 through the member 3 bodily blown away when the fuse blows. This provides an instantaneous relief for the pressure gases and avoids placing excessive strain upon the glass body portion.

The sleeve 3 is provided with diametrically 60 opposed slots 6 which are open at their upper ends and which are provided with rounded shoulders at their lower ends. A transverse, relatively strong arch like member or bridge member 7 has its ends rounded and seated loosely within the 65 slots 6 and resting upon the rounded shoulders at the bottom of such slots. This arch like member 7 is in reality a strong metal strip which is a support for the composite fuse link.

70 The composite fuse link is preferably formed of an upper and a lower portion, the upper portion consisting of two ribbon like members 8 between which a single ribbon like member 9 forming the lower portion is secured. The upper ribbon like members of the fuse link pass through 75 a central aperture formed in the support 7, pass

over the upper face of the support, and have their ends wrapped or positioned beneath the rounded ends of the member 7. When pressure is applied to the fuse link, it is apparent that the supporting member 7 acts like a toggle and causes a great pressure to be exerted against the ends of the fuse link thereby insuring excellent electrical contact between the upper ends of the fuse link and the upper contact 3. If desired, a hole 8' may be formed through the upper strips 8. 10

The lower member 9 of the fuse link is received between the members 8 and is soldered to such members. This forms an intermeshing or overlapping of the flat ribbon like fuse strips, which are preferably formed of ribbon, providing a suitable 15 resistance to heat the soldered joint.

The material of which the ribbons or other shaped members forming the fuse link, either in the form now being described or in the forms subsequently described, may be of any suitable material, such as a nickel chromium alloy, nickel, copper, chromium D, or any other material selected for its particular characteristics. For example, different materials for different amperage links are employed. A high resistance material 20 like a nickel chromium alloy is employed for low amperage links, and a very low resistance material, such as copper, may be employed for high amperage links, adjusting the material and the thickness of the material so as to give a very constant I^2R development at the soldered joint. This I^2R is that which is required to raise the solder to the melting temperature.

It is, therefore, apparent that a given solder having a substantially definite melting point may 35 be employed, and that the heat developed at the soldered joint may be constant for all sizes of fuses, the capacity or rating of the fuse being varied preferably by varying the thickness of the fuse strips or members and their composition. 40 This enables the manufacturer to use substantially the same dies or apparatus for forming the members of the fuse link, although fuse links of widely different ratings may be selectively produced as desired by means of the characteristics 45 of this invention which have been outlined immediately above.

The intermediate portion of the composite fuse link is reduced in cross-section by narrowing the ribbon like members, as indicated generally at 10 50 in Figure 2, so that the cross-sectional area remains approximately the same throughout the entire length of the fuse link. If desired, the intermediate portion of the fuse link may be covered by a cork or other member 11. 55

The lower member 9 of the fuse link continues downwardly and is supplemented by an additional member 9' riveted or otherwise secured thereto to provide a double thickness, or two ribbon like members for the lowest part of the 60 lower portion of the composite fuse link. These ribbon like portions are separated and are positioned beneath inturned channel shaped arms of a lower fitting 12. The arms 12 are preferably integral with each other and are approximately 65 U-shaped formation having a flat bottom connecting yoke 13, see Figure 1. The channel portions of these arms are indicated more clearly in Figure 5. The upper ends of the arms 12 converge or approach each other, as shown most 70 clearly in Figure 1.

An inverted V-shaped wedging member 14, see Figure 1, is positioned between the portions 9 and 9' of the fuse strip and the arms 12 of the lower fitting, so that when the lower fitting or con- 75

ducting portion is drawn downwardly, the fuse link is tightly wedged against the arms 12, see Figure 5, thereby securing an excellent electrical contact.

- 5 It is to be noted at this point that the electrical connection between the upper and lower ends of the fuse link and the adjacent conducting portions is secured, in this form of the invention, without the use of screws or other fasteners of this type. This construction also affords a wedging or binding contact between the fuse ends and the conducting portions, thereby securing good contact and reducing the heating at these points.
- 10 As shown in Figure 1, it is preferable to bend the ends of the members 9 and 9' over the bottom ends of the member 14 to facilitate positioning of the parts.

15 The conducting member or fitting just described is secured to a transverse plate 15. Preferably the yoke 13 is locked to the plate or bar 15 by upwardly and inwardly turned ears 16 formed integrally with the bar 15, as shown in Figures 1 and 4. The bar 15 is soldered or otherwise secured to a flexible leader or stranded conductor 17 whose lower end is secured to the lower terminal or contact member 2.

20 A helical spring 18 loosely surrounds the leader 17 and is secured to the lower contact 2 in any suitable manner. The bar 15 extends between convolutions of this spring and thus provides a very secure attachment of the spring to the lower member 12.

25 It is preferable to provide some form of protection for mechanically protecting the diaphragm 5, see Figures 1 and 2. This protecting means may take the form of a cap 19 provided with spring fingers 20 which snap beneath the bottom edge of the ring nut 4.

30 The tubular body portion is preferably completely filled with some arc extinguishing liquid, such as carbon tetrachloride. Obviously the tubular body portion may be filled to any desired height, although the complete filling is probably 45 the simplest.

35 When the fuse blows, the diaphragm 5 is ruptured around its margins and blown, together with the cap 19, from the fuse body. The arch shaped supporting member 7 is released from the 50 pressure and consequently wedging of its ends and the adjacent portion of the fuse against the annular member 3 is instantly relieved, and this arch shaped member and the remaining upper portion of the fuse is blown bodily from the tubular body portion.

40 There is thus no possibility of choking with a consequent bursting of the body portion.

45 The fuse link may take other forms than that shown in Figures 1 and 2. For instance as shown in Figure 6, the fuse link may consist of a pair of upper ribbon members 21 which are soldered to a lower ribbon member 22.

50 In the form shown in Figure 7 and the sectional view Figure 15, the fuse link may consist 55 of two wire like members, an upper member 23 and a lower member 24. These wire like or rounded members may have reduced portions 23' and 24' cut to half thickness and soldered together, particularly as shown in Figure 15. The upper member 23 may be secured to the bridge member 25 in any suitable manner. In the form shown in Figure 7 it is attached by means of a bolt 26 in one of the arms of the bridge member.

55 Figure 8 shows a further form of fuse link in which a pair of upper wires or other shaped

members 27 receive between them a lower wire or other shaped member 28 which is soldered to the upper wires at their overlapping portions, particularly as shown in Figure 16. Obviously other shapes may be employed if desired. The upper ends of the members 27 are secured by bolts or screws 29 to the arms of the bridge member 30.

60 Figure 9 shows a form of fuse link in which a pair of spaced ribbon like or other shaped upper members 31 are secured to the underside of the bridge member 32 by bolts or screws 33. A U-shaped lower member 34 has its arms soldered flatly to the members 31 and is preferably provided with a reinforcing metal piece 35 in its horizontal loop to which the tension spring may be attached, and to prevent folding or drawing of the arms of the member 34 towards each other.

65 Figure 10 shows a further form in which the upper strip 36 of ribbon or other shaped member 20 is not joined directly to the lower member 37 but indirectly by means of symmetrically placed, overlapping intermediate portions 38, to which both upper and lower members are soldered. The upper end of the member 36 may be attached 70 to the bridge piece 39 in any suitable way, as by means of the bolt 40.

75 Figure 11 shows a further form of construction in which ribbon like upper members 41 receive between them a lower ribbon like member 42 which is soldered thereto, as previously described.

80 This construction is similar to that shown in Figure 6 except that the upper ends of each of the members 41 are separately attached to the bridge piece 43 by means of screws or bolts 44, 35 or other fastening means.

85 Figure 12 shows a further form of the invention in which the upper member of the fuse link consists of a tubular member 45 which receives within its lower end a round or wire like lower member 46, such members being soldered together, as previously described. Preferably the upper portion of the tubular member 45 is flattened and split to provide tongues which may be oppositely folded, as indicated at 47. These 90 tongues are secured to the bridge member 48 in any suitable manner, as by means of the bolts 49.

95 In the form shown in Figure 13 a different type of bridge member is employed. This bridge member, acting like the other previously described bridge members, secures the same toggle effect as the other members. However, it consists of two hingedly joined arms 50 which may be joined by means of a pintle pin or other member 51, as shown in Figures 13 and 14. The fuse 100 link may be of any desired type.

105 In the form shown, two wire or ribbon members 52 constitute the upper portion of the fuse link and receive between them a lower member 53. The upper members 52 are looped over the 110 pintle pin 51, as shown most clearly in Figure 14, and are secured to the arms 50 by means of the screws or bolts 54.

115 It is to be noted that in this form of construction the upper contact member 3 of the body portion of the fuse is provided with slots which terminate in abrupt shoulders 55, as shown in Figure 13. This construction provides a sharp corner within the slot and the ends of the members 50 are bevelled at a sharper angle than that 120 between the shoulders 55 and the vertical portions 56 of the slots, and consequently such sharply pointed or bevelled ends of the members 50 have a line bearing with the corner portions formed by the faces 55 and 56 of the slots. (Fig- 125 75

ure 13 is a fragmentary line section of the member 3.)

In all forms of the invention it will be seen that the toggle effect is obtained for the upper supporting or bridge member, and that a very secure electrical contact is obtained for the fuse strip.

The relatively heavy spring 18 insures instant separation of the two portions of the fuse when blowing occurs whether from large overloads or relatively small overloads.

The fuse can be readily re-fused and used over and over again. In each form of the invention the attachment of the fuse link is of very simple construction and is easy to operate.

Further it is to be particularly noted that the soldered joint in all forms of the invention is in pure shear and is not subjected to tensile stresses, which would cause an inaccuracy in the functioning of the fuse, as has been developed in great detail hereinabove.

The fuse link itself is remarkably sturdy, although it may be built for small overloads or in small capacities. This permits the free handling of the fuse link in re-fusing without danger of damage thereto.

It is to be distinctly understood that although a cork 11 has been shown only in the form illustrated in Figures 1 and 2 of the drawings, that nevertheless it may be used with any other form of the invention. Further, it is to be noted that the cork could be replaced by some other material or some other type of member which would offer a greater area of contact, either with the outrushing gases or with the pressure gases below its bottom face, so that it would assist in the action of clearing the fuse, as will be hereinafter described, although it has been found from actual practice that the cork is well suited to this purpose. The invention, however, is not limited to the use of a cork alone, but other material or other members could replace the cork.

It is to be noted that the cork actually furnishes an additional area of contact with the outwardly rushing gases when the fuse blows and so assists in quickly removing the fuse, as it is bound thereto. This action takes place not only from the pressure developed on the underside of the cork by the outwardly rushing gases, but also by the frictional contact of these outwardly rushing gases with the side of the cork. Obviously another member could replace the cork and come within the spirit of this invention.

In addition to these functions, the cork performs an additional function. It mechanically binds the parts of the fuse strips together and assists in preventing breaking of the fuse, particularly during handling or re-fusing. It prevents kinking of the fuse or breaking of the fuse at the soldered joint, as it provides a mechanical reinforcing agency for this portion of the fuse strip, particularly as it extends completely over the soldered joint and over the ends of the soldered joint.

It will be seen that a novel form of fuse has been provided by this invention in which the I^2R watts developed at the soldered joint is substantially constant, irrespective of the rating or capacity of the fuse, and that the calibration of fuses of different ratings or the production by quantity production methods of fuses of any de-

sired rating may be easily followed with a resulting substantially constant accuracy.

Although this invention has been described in considerable detail, it is to be understood that such description is intended as illustrative rather than limiting, as the invention may be variously embodied and is to be interpreted as claimed.

I claim:

1. A liquid fuse comprising a tubular body portion, an upper annular contact, an upwardly bowed member spanning said annular contact and having its ends supported from said annular contact, a fuse link having an upper portion formed of two strips independently secured to said upwardly bowed member, said fuse link extending downwardly from the central portion of said upwardly bowed member, a lower contact electrically connected to said fuse, and a spring for placing tension on said fuse link. 15

2. A fuse comprising an annular contact, a fuse link, a toggle member supporting said fuse link and forcing an end of said fuse link into engagement with an inner wall of said contact, a second contact electrically connected to the other end of said fuse link, and a spring for placing tension on said fuse link. 20

3. A fuse comprising a contact, a conducting fitting, a spring tending to pull said fitting in a direction away from said contact, a fuse link between said contact and fitting, and wedging means at each end of said fuse link for forcing said fuse link into binding engagement with said contact and said fitting, the wedging action being produced by the pull of said spring, said fuse link being in direct contact with both said contact and said fitting and said wedging means increasing the contact pressure directly between said fuse link and said contact and said fitting. 30

4. A liquid fuse comprising a tubular body portion adapted to hold an arc extinguishing liquid, an annular upper contact and a lower contact carried by said body portion, said annular contact having opposed notches, an upwardly bowed member having its ends positioned within said notches, a fuse link extending through the central portion of said member and having a pair of upper ends passing through said member, a lower contact, a spring having its lower end secured to said lower contact, a fitting secured to the upper end of said spring, said fuse link having a lower portion engaging said fitting, and a wedge for forcing said lower portion against said fitting. 40

5. A liquid fuse comprising a tubular body portion adapted to hold an arc extinguishing liquid, a lower and an upper contact carried by the body portion, said upper contact having opposed shouldered portions, an arch shaped member having projecting arms seated on said opposed shoulders and supported by said shoulders, a fuse link suspended from an intermediate portion of the arch shaped member and having one end positioned between one of the arms of said arch shaped member and one of said shoulders, and a spring operatively coupled to the lower end of the fuse link and to the lower contact, said arch shaped member having a toggle action forcing the upper end of the fuse link into direct binding engagement with said upper contact. 55

RALPH H. EARLE.
